W. D. & W. C. RALSTON.
ADJUSTABLE CURTAIN SHADE BRACKET.
APPLICATION FILED AUG. 4, 1916.

1,230,778.

Patented June 19, 1917.

UNITED STATES PATENT OFFICE.

WILLIAM D. RALSTON AND WILLIS C. RALSTON, OF NEW MARION, INDIANA.

ADJUSTABLE CURTAIN-SHADE BRACKET.

1,230,778.

Specification of Letters Patent. Patented June 19, 1917.

Application filed August 4, 1916. Serial No. 113,155.

To all whom it may concern:

Be it known that we, WILLIAM D. RALSTON and WILLIS C. RALSTON, citizens of the United States, residing at New Marion, in the county of Ripley and State of Indiana, have invented certain new and useful Improvements in Adjustable Curtain-Shade Brackets; and we do hereby declare the following to be a full, clear, and exact description of the invention, such as will enable others skilled in the art to which it appertains to make and use the same.

This invention relates to an adjustable curtain shade bracket and has for its primary object the provision of means whereby the device may be readily and quickly applied to a window frame without the employment of nails or screws and which obviates the use of a tool to apply and remove the device, thereby preventing the window frame from being marred or injured.

Another object of this invention is to provide a pair of jaws adjustably connected together, whereby the door may be applied to window frames of several sizes.

A further object of this invention is to provide a bar pivoted to one of the jaws and adjustably secured to the other jaw, whereby upon operating the lever, the jaws will be moved in the direction of each other to tightly clamp a window frame.

A still further object of this invention is to provide a slot in the bar and having a plurality of teeth formed on the wall thereof to be engaged by a dog actuated by the lever, whereby upon movement of the lever, the dog will engage the teeth and draw the jaws in the direction of each other.

With these and other objects in view as will become more apparent as the description proceeds, the invention consists in certain novel features of construction, combination and arrangement of parts as will be hereinafter more fully described and claimed.

For a complete understanding of our invention, reference is to be had to the following description and accompanying drawing, in which:—

Figure 1 is a fragmentary front elevation of a window frame, illustrating our invention applied thereto,

Fig. 2 is a vertical sectional view of an adjustable curtain shade bracket, constructed in accordance with our invention, and 55

Fig. 3 is a top plan view of the same.

Referring in detail to the drawing, the numeral 1 indicates the upper portion of a window frame of any desired construction, having adjustable curtain shade brackets, 60 constructed in accordance with our invention secured to each end thereof. Each of the adjustable curtain shade brackets are identical in construction except the supporting brackets to which the ends of a curtain 65 shade roller is attached, one of the brackets being provided with the ordinary slot and the other bracket with the aperture to cooperate with the construction of the ordinary curtain shade roller. As both of the 70 adjustable curtain shade brackets are identical in construction except for the aforementioned parts, it is not deemed necessary to now describe each of them in detail as a description of one of them applies to both. 75

A pair of jaws 2 and 3, each constructed from a metallic plate having one of its ends bent to form jaw engaging portions 4 that engage in operation the upper and lower edges of the window frame 1. A pair of 80 relatively spaced ears 5 are riveted or otherwise secured to the jaw 3 and are struck up from a single length of metal so that each of the ears are secured together by a strip 6. A bar 7 is pivoted between the ears 5 as 85 illustrated at 8 and has an elongated slot 9 therein, the lower wall of which is provided with a plurality of teeth 10.

A pair of relatively spaced ears 11 are riveted or otherwise secured to the jaw 2 90 and are struck up from a single length of metal so as to secure the ears together as illustrated at 12. The ears 11 are provided with either the slot or the aperture to receive the ends of the ordinary window shade 95 roller and one of the ears 11 has formed thereon an extension 13 to which is pivoted an operating lever 14. The pivot 15 of the operating lever 14 extends through the elongated slot 9 of the bar 7 which is 100 slidably received between the ears 11. A plate 16 is secured to the pivot 15 and disposed upon the opposite side of the bar 7 from the operating lever 14 and has ec-

centrically connected thereto a dog 17, the free end of which is bent at right angles to engage the teeth 10 of the bar 7.

In operation when desiring to apply the device to a window frame, the jaws 2 and 3 are moved apart approximately the width of the window frame by swinging the operating lever 14 upwardly, freeing the dog 17 from the teeth 10 of the bar 7. By swinging the operating lever 14 downwardly in parallel relation with the bar 7, the dog 17 simultaneously engages one of the teeth 10 of the bar 7 and bears the bar in the direction of the jaw 2, thereby moving the jaws 15 in the direction of each other to tightly clamp the window frame. If one movement of the operating lever is not sufficient to tightly clamp the jaws to the window frame, by swinging the lever upwardly, the dog 17 20 will be moved forwardly engaging the next adjacent notch and by downward movement of the lever, the bar again will be moved in the direction of the jaw 2 tightly clamping the jaws upon the window frame.

While we have shown and described the preferred embodiment of our invention, it will be understood that minor changes in construction, combination and arrangement of parts may be made without departing 30 from the spirit and scope of the invention as claimed.

Having thus described our invention, what we claim is:

1. A device of the character set forth comprising a pair of jaws, means for securing a shade roller to one of the jaws, a pair of relatively spaced ears secured to the other jaw, a bar pivoted to said ears, and means for adjustably securing the bar to the other jaw for moving said jaws in the direction of each other to clamp a window frame.

2. A device of the character set forth comprising a pair of jaws, a pair of relatively spaced ears secured to one of the jaws, a bar pivoted to said ears, a pair of relatively spaced ears secured to the other jaw and slidably receiving said bar, means for securing a shade roller to the second

mentioned pair of ears, and means carried by the second mentioned ears for an engagement with the bar to move the jaws in the direction of each other to clamp a window frame.

3. A device of the character set forth comprising a pair of jaws, a bar pivoted to one of the jaws and having an elongated slot therein, a plurality of teeth formed on the wall of the elongated slot, a pair of relatively spaced ears secured to the other jaw, and slidably receiving the bar, means for securing a shade roller to the ears, an extension formed on one of said ears, a lever pivoted to said extension, a plate carried by the pivot of the lever and disposed upon the opposite side of the bar from the lever, and a dog eccentrically secured to the plate for an engagement with the teeth to move the jaws in the direction of each other upon movement of the lever to clamp the jaws upon a window frame.

4. A device of the character set forth comprising a pair of jaws, a pair of relatively spaced ears secured to one of said jaws, a bar having one end thereof pivoted to said ears, a pair of relatively spaced ears secured to the other jaw and slidably receiving the free end of the bar, means for securing a shade roller to the second mentioned pair of ears, said bar having an elongated slot, means formed on one wall of the slot, an extension formed on one of the last mentioned pair of ears, a pivot carried by said extension and extending through the slot, a handle secured to the pivot, a plate secured to the pivot and disposed upon an opposite side of the rod from the lever, and a dog eccentrically connected to the plate and adapted to engage the teeth upon operation of the lever to move the jaws in the direction of each other.

In testimony whereof we affix our signatures in presence of two witnesses.

WILLIAM D. RALSTON.

WILLIS C. RALSTON.
